UNITED STATES PATENT OFFICE.

FRED A. NEIDER, OF AUGUSTA, KENTUCKY.

TUFTING-BUTTON FOR CUSHION-SEATS.

SPECIFICATION forming part of Letters Patent No. 630,553, dated August 8, 1899.

Application filed December 4, 1897. Serial No. 660,756. (No model.)

To all whom it may concern:

Be it known that I, FRED A. NEIDER, a citizen of the United States, and a resident of Augusta, in the county of Bracken and State 5 of Kentucky, have invented certain new and useful Improvements in Tufting-Buttons for Cushion-Seats, of which the following is a specification.

My invention is an improvement in tufting-buttons for cushion-seats, and particularly in the button-back, with its clenching-prongs formed integral therewith. In buttons of this kind heretofore used the tines or clenching-prongs were formed integral with the button-back, but of a uniform width from the back to the tapered point. It has been found in use that buttons so constructed when applied and having their clenching-prongs turned over on the button or foundation upon which 15 the upholstering material is secured had an inclination to bend near the body of the button-back, leaving a wedge-shaped or curved space between the turned prongs and the back of the button, which in use brought all 20 the strain upon the clenching-prongs at their base or juncture with the button-back. In use the prongs had a tendency either to straighten out or break off at an angle-bend near the body of the button.

30 The object of my invention is to overcome this defect and form the tines or clenching-prongs with a heavy base back of the button-disk and taper this base down to a point some distance from the back of the button to its 35 junction with the straight or parallel sides of the tines, so that in bending the inclination to bend is at the base of the tapered base, forming practically a neck for the button between the button-back and the angular bend 40 of the tines when turned over the bottom or base of the cushion-seat, whereby the strain upon the button and the tines is a direct strain, having no tendency to break the clenching-prongs near the base of the button nor to 45 straighten them out beneath the cushion-base.

The invention will be fully understood from the following description of the accompanying drawings, in which—

50 Figure 1 is an inverted perspective view of a tufting-button embodying my invention. Fig. 2 is a central vertical sectional view of the same through line $x-x$ of Fig. 1. Fig. 3

is a perspective view of the button, showing one of the clenching-prongs bent at an angle to the tapering base. Fig. 4 is an inverted 55 plan view of the button-back as it comes from the stamping-machine and before the clenching-prongs are turned at right angle to it, as shown in the preceding figures. Fig. 5 is a detail view in central vertical section of the 60 cushion with my button applied to form the tufts.

The cap A is secured to the body of my improved back B in the usual manner by having its edges flanged or turned over the edge 65 of the back. The back B, with its clenching-prongs b, having the flaring-base b' tapering from its junction with the body to the point b^2 , is stamped out in the usual manner, with the single exception of the base b' flaring 70 from the point b^2 to the points b^3 , which sever it from the body of the base and determines the line at which it is bent at a right angle to the base to pass through perforations in the foundation or base C of the seat. 75

The tufting-button is applied in the usual manner, as illustrated in Fig. 5—that is, the filling D is first placed upon the base, the covering material E turned over and secured to it and perforated opposite the perforations 80 in the foundation to receive the clenching-shanks b of the tufting-buttons, which are passed through the material, through the perforations in the base, pressed down to the position shown in Fig. 5, and clenched over 85 underneath the base. As the prongs b are bent over the base they naturally bend at the point b^2 flat upon the bottom of the base, leaving necks or straight portions between their angular bends and the bottom of the 90 button, so that in use there is no tendency to straighten out the bends, as the line of the bend is clearly defined and at a right angle to the base. By this means a cushion is left between the covering goods between the bottom 95 of the button and the base, which prevents all tendency of the prongs to break either at their juncture with the body or at the point b^2 , where they bend around the base 100 of the cushion.

I have shown my clenching-prongs having a plain taper from the base to the point where it joins the parallel portions b of the clenching-prongs, but it would be an inferior modi-

ification of my invention to form the base with a square or rounded shoulder to define the line at which the prongs should bend when inserted for use, and I have also shown 5 the common metallic flanged cap covering the back; but it is obvious to those skilled in the art that my back and clenching-prongs may be used with any of the well-known forms of caps or top coverings, and while I 10 have shown my invention in the best form which is known to me I do not desire to be limited to the specific details shown and described.

What I claim as my invention is—

15 1. The button-back having formed integrally with it clenching-prongs adapted to be

bent at right angles to the back, said prongs having enlarged bases merging into the parallel sides of the clenching-prongs, said back so cut as to determine the line at which the 20 prongs are bent when in use, substantially as shown and described.

2. The hereinbefore-described tufting-button consisting of the cap having clenching-prongs projecting from its back, said clenching-prongs having an enlarged base tapering to the parallel sides of the clenching-prongs, substantially as shown and described.

FRED A. NEIDER.
